UNITED STATES PATENT OFFICE

154,407

DESIGN FOR A BIRD FEEDING HOPPER

Freda C. McCutcheon, Superior, Wis.

Application September 18, 1946, Serial No. 133,390

Term of patent 14 years

(Cl. D31—2)

To all whom it may concern:

Be it known that I, Freda C. McCutcheon, a citizen of the United States, residing at Superior, in the county of Douglas and State of Wisconsin, have invented a new, original, and ornamental Design for a Bird Feeding Hopper, of which the following is a specification, reference being had to the accompanying drawing, forming part thereof.

In the drawing

Fig. 1 is a perspective view of a bird feeding hopper, showing my new design;

Fig. 2 is a front elevational view of Fig. 1 except that the cover is closed.

Fig. 3 is a side elevational view of Fig. 2.

The characteristic features of my design for the bird feeding hopper disclosed reside in the specific configuration of the curved lower portion

terminating in the frontal triangular tip, all as shown.

I claim:

The ornamental design for a bird feeding hopper, as shown and described.

FREDA C. McCUTCHEON.
